UNITED STATES PATENT OFFICE.

SAMUEL B. WILLIAMS, OF BROOKLYN, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed April 12, 1924, Serial No. 706,014. Renewed April 5, 1926.

This invention relates to telephone exchange systems and particularly to such systems as employ automatic switches in the establishment of connections.

5 The invention has for its object an improved means for identifying the particular switch or group of switches in which a selected trunk terminates.

The invention is particularly adaptable 10 to telephone exchange systems such as disclosed in the patent to S. B. Williams, No. 1,517,331, issued December 2, 1924, and also in the copending application of W. W. Carpenter Serial No. 703,362, filed April 1, 15 1924, wherein a common controlling mechanism of the marker type is used for controlling the operation of selector switches. A number of so-called frame connectors are also provided for the purpose of placing the 20 proper set of selector switches under the control of the marker, the choice of a particular frame connector being determined by the setting up of a record in the marker.

A feature of the invention, therefor, is 25 the means for controlling the selection of the proper frame connector directly from contacts of the sender selector switch.

Other features and advantages will become apparent after a consideration of the 30 detailed description.

Referring to the drawing, Figs. 1 to 5 when arranged in the order shown in Fig. 7 disclose a sufficient portion of a telephone system to clearly illustrate the invention.

35 Fig. 1 discloses a line switch of the coordinate type, and one of a number of outgoing trunks with associated controlling apparatus.

Fig. 2 illustrates one of a number of district selector switches, together with a number of outgoing trunks.

Fig. 3 shows a sender selector switch with its associated non-interfering starting circuit, and also an allotter switch for pre-selecting an idle sender.

45 Fig. 4 to the left of the broken line shows a number of frame connectors and certain controlling circuits. To the right of the broken line are shown a number of marker relays and a schematic diagram of the marker testing mechanism.

50 Fig. 5 to the left of the broken line shows a portion of a subscriber's sender, while to the right of the broken line is shown one 55 of a number of sender connectors for con-

necting a selected sender with an idle marker. In this figure are also shown a number of non-interfering starting circuits associated with the sender connector.

Fig. 6 comprises a schematic diagram 60 showing a portion of a telephone system embodying the features of the present invention.

General description.

65

Referring to Fig. 6, the subscribers' lines 608, 609 enter the exchange and have an appearance in a number of coordinate line switches 600. Outgoing from these line switches are a number of trunks 601, 602, 70 etc., which terminate in district selector switches 610, 611, 612, etc. These district switches are arranged in a plurality of groups, one group being represented by switches 610 and 611 and another group by 75 switches 612 and 613. The trunks outgoing from the line switches are shown distributed in an arbitrary manner among the different groups of district switches. A sender selector 620 causes the association of 80 an idle register sender as 630 with the calling line. When the designation of the called line has been recorded on the register sender 630, a device 640 is operated to connect the recording sender with an idle one 85 of the markers as 650 for the purpose of transferring a portion of the record. There are also provided a number of frame connectors 660 and 661, each of which may be associated with any marker and is individual to a group of district selector switches. Thus frame connector 661 is individual to the group of switches including 90 switches 612 and 613. From an inspection of Fig. 6, it will be apparent that the trunks 95 outgoing from the line switches preserve the same grouping before the sender selector 620 as they do before the district switches 610, 612, etc. That is to say the vertical row of contacts 605 in the sender 100 selector switch 620 corresponds to the group of district switches represented by switches 612 and 613. In a similar manner vertical row of contacts 606 corresponds to the group of district switches represented by switches 105 610 and 611.

110 Since the frame connectors 660, 661, etc., are accessible to any of the markers 650, 651, etc. it becomes imperative that the proper frame connector be operated corre-

sponding to the particular group of district switches in which the extended calling line appears. Thus, if trunk 601 has been selected by a calling line, frame connector 661 must be operated, since trunk 601 has an appearance only in the group of district switches with which frame connector 661 is associated. Therefore, by identifying the particular row of vertical contacts of the 10 sender selector switch 620 in which the selected trunk has an appearance, means is provided for selecting the proper one of the frame connectors 660, 661, etc.

The line switch 600, sender selector switch 15 620 and district selector switches 610, 612 etc., are of the coordinate type such as shown and described in the patent to S. B. Williams, No. 1,517,331, issued December 2, 1924.

20 *Detailed description.*

When a subscriber, as the subscriber at the line 101, initiates a call, the line switch 100 is operated in the manner described in detail in the above mentioned patent to S. B. Williams, thus causing line 101 to be connected by means of a horizontal link as link 102 with an idle outgoing trunk 120. At the same time ground is extended to the 25 sleeve conductor of trunk 120, and thence through the lower middle armature and contact of relay 112, normal contact of relay 111, conductor 150, to battery through the winding of relay 301 which corresponds to the line relay and is individual to trunk 120. Relay 301 closes a locking circuit for itself, through its right inner armature and contact, conductor 155, lowermost armature and contact of relay 112, lower middle armature and contact of the same relay to the 30 grounded sleeve conductor of trunk 120. Relay 301 in operating connects ground through its right outer armature and contact, conductor 156, to battery through the winding of slow release relay 111. Relay 111 operates and applies ground to the sleeve conductor of the trunk, thus providing a 35 substitute holding circuit for relay 301, and at the same time maintaining the connection through switch 100 as described in the patent to S. B. Williams hereinbefore mentioned.

Relay 301 also connects ground through its left outer armature and contact, conductor 351, right armature and back contact of relay 303, to battery through the winding of relay 302. It will be observed that the group of relays 302, 303 and 304 is individual to a particular group of trunks represented by conductors 330 and conductors 331. Similarly the group of relays 332, 333 and 334 is individual to a second group of trunks. Relay 302 closes an obvious operating circuit for common relay 307. Assuming that no trunk in any other group is in the process of being associated

with a sender, then all relays similar to relay 302 are normal, and a circuit is closed from battery through the left hand winding of relay 304, left armature and front contact of relay 302, left armatures and back contacts of intermediate relays similar to 302, conductor 352, right armature and back contact of relay 305 to ground at the armature and contact of relay 306. Relay 304 closes a locking circuit for itself through its right inner armature and front contact, winding of relay 305, to the above traced ground. Relay 305 operates in this circuit thus preventing simultaneous connections through the switch 300. Relay 305 also closes an obvious operating circuit for slow-release relay 312. The operation of relay 304 also closed an obvious operating circuit for relay 303 which locks through its left armature and contact, left armature and contact of relay 307, left armature and contact of relay 308 to ground, thus breaking the operating circuit of relay 302 which releases. When relay 304 closed its right outer armature and front contact, a circuit was completed from battery through the winding of vertical operating magnet 309, right outer armature and front contact of relay 304, right armature and front contact of relay 305, to ground at the armature of relay 306. Magnet 309 attracts its armatures and prepares the vertical row of contacts 318 by actuating rod 324. At the same time a circuit was closed to operate vertical magnet 310 associated with the vertical row of contacts 323 corresponding to a preselected idle sender. The circuit for this purpose may be traced from battery through the winding of magnet 310, brush 320 of the allotter switch 350, armature and contact of relay 311, conductor 353, left armature and contact of relay 306 to ground at the armature of relay 305. Magnet 310 attracts its armatures and prepares the vertical row of contacts 323 by actuating rod 326. At the same time ground is connected through the lower inner armature of magnet 310, conductor 550, brush 321 of the allotter switch 350, stepping magnet 355 to battery through the winding of relay 311. Switch 350 advances by means of this self-interrupting circuit until a set of terminals is reached corresponding to the next idle sender, when the energizing circuit for magnet 355 is broken and switch 350 comes to rest. Magnet 310 also closed an obvious locking circuit for itself in series with the winding of relay 306 which operates and opens the operating circuit of relay 312 as soon as allotter switch 350 steps forward. However, relay 312 is slow to release permitting the following operations to take place.

Assuming that link 341 is the first idle link in the group of links before which conductors 330 have an appearance, then a cir-

cuit is closed for operating horizontal group relay 313 which is associated with this latter group of links. This circuit may be traced from battery through the right hand winding of relay 313, left inner armature and contact of relay 301, conductor 354, left outer armature and contact of relay 304, left armature and contact of relay 327 to ground at the armature of magnet 309. Relay 313 closes a locking circuit for itself from battery through its left hand winding and left contact, left armature and back contact of relay 328, winding of relay 327 to ground at the armature of magnet 309. Relay 327 operates in this circuit. A circuit now is closed to operate horizontal magnet 314 associated with the idle link 341, from battery through the winding of magnet 314, armature and back contact of relay 315, armature and front contact of relay 316, right armature and front contact of relay 313, right armature and back contact of relay 328, right armature and front contact of relay 327 to ground at the right hand armature and contact of relay 306. Magnet 314 operates in this circuit and completes the connection from the set of conductors 330 through horizontal link 341 to the set of conductors 360 leading to the selected sender. With the switch 300 operated the ground at the contact of magnet 310 is extended through the contacts of switch 300 conductor 153 to battery through the winding of relay 112. Relay 112 operates thus connecting the calling line directly through the sender selector with the selected sender.

When relay 312 releases subsequent to the operation of horizontal magnet 314, the holding circuit for relays 304 and 305 is broken and these relays now release in turn releasing magnets 309 and 310 and relay 306, the connection through the switch 300 being maintained by horizontal magnet 314 in the manner described in the patent to S. B. Williams above mentioned. Should another trunk be awaiting connection through switch 300 while the foregoing operations were taking place, relays 333 and 334 corresponding to this latter trunk are operated and relay 303 corresponding to the first mentioned trunk remains locked through its left armature and contact, to ground at the left inner armature and contact of relay 334, thus preventing a second trunk in the same group of trunks represented by conductors 330, being connected through switch 300 before waiting connections in other groups have been so completed. Should, however, a connection be waiting in the first-mentioned group, all intermediate relays similar to relay 302 are released and a circuit is closed for relay 308 through the left armatures and back contacts of these relays in series, conductor 352 to ground through the right armature and

back contact of relay 305. The operation or relay 308 opens the holding circuit of relay 303 which now releases, and permits other trunks in group, represented by conductors 330, to be connected through switch 300 with an idle sender.

When magnet 309 operated it connected ground through its lowermost armature and contact, conductor 356, connecting block 370, conductor 357, left normal contact of relay 503 to battery through the winding of relay 511. At this point it will be observed that the armatures of certain of the vertical magnets as 309 and 339 are cross connected by means of block 370 to the winding of frame identifying relay 511, while the corresponding armatures of other vertical magnets, as magnet 338 are left blank for purposes hereinafter described.

As soon as connection was completed through switch 300, an impulsing circuit was closed from battery through the winding of relay 502, conductor 359, contacts of switch 300, conductor 152, ring side of the trunk 120, contacts of line switch 100, through the subscriber's loop, back over the tip side of the line, contacts of switch 100, tip side of the trunk, conductor 151, conductor 358 to ground through the winding of retardation coil 539. Relay 502 operates in this circuit and closes an obvious operating circuit for slow release relay 503. Relay 503 applies holding ground to conductor 550 to take the place of the ground which is removed when magnet 310 releases. Relay 503 also closes through its left armatures an obvious holding circuit for the identifying relay 511, this latter relay being now maintained energized independently of vertical magnet 309.

The calling subscriber now dials the designation of the wanted line, setting up a corresponding record on the registers A, B, C, etc. in the manner described in detail in the above mentioned patent to S. B. Williams. After the digits have been thus recorded, relay 512 operates and completes a circuit from ground through its armature and contact, upper winding of relay 504 to battery at the right outer armature and contact of relay 505. Relay 504 operates and completes a locking circuit for itself in series with the winding of relay 505. Relay 505 also operates, thus preventing more than one sender being connected simultaneously, through contacts of sender connector 500, with the same marker. The operation of relay 505 also closes a circuit from battery through the winding of magnet 513, upper armature and contact of relay 504, right inner armature and contact of relay 520 to ground at the armature of relay 505. Magnet 513 completes an obvious locking circuit for itself to ground at the left armature of relay 505.

It will be observed that the group of con-

ductors, as 560, leading to a marker, have an appearance in a particular row of contacts in the sender connector 500. Thus, the conductors 560, which are individual to the marker shown in Fig. 4, have an appearance in vertical row 514. In a similar manner, a corresponding set of conductors, as 561, leading to another marker are shown terminating in a vertical row of contacts 515. Assuming that the marker associated with the vertical row 514 is idle, then when relay 504 operates it closes a circuit from battery at the left inner armature and contact of relay 507, upper winding of relay 501, lower armature and back contact of relay 509, lower outer armature and front contact of relay 504, right outer armature and back contact of relay 520 to the grounded conductor 521. Relay 501 closes an obvious locking circuit for itself in series with the winding of relay 507. With relays 501 and 507 operated, a circuit is closed for operating magnet 517 from battery through its winding, lower middle armature and contact of relay 501 to ground at the left outer armature and contact of relay 507. The operation of magnet 517 connects the set of conductors 560 directly with the register sender, allowing the recorded designation to be transferred to the selected marker in the manner described in the previously mentioned patent to S. B. Williams. Relay 507 also closes a circuit through to lower contact of relay 501, for operating the cutoff relay 520.

If when relay 504 operates, the marker associated with conductors 560 is busy, then relay 509 is operated and a circuit is closed to operate starting relay 510 associated with the next idle marker. The circuit for this purpose may be traced from battery at the left inner armature and contact of relay 518, upper winding of relay 510, lower armature and back contact of relay 516, lower armature and back contact of relay 522, upper armature and contact of relay 501, locking contact and armature of relay 509, lower armature and front contact of relay 504 to the grounded conductor 521 through the right outer armature and contact of relay 520. The operation of relay 510 causes the successive energization of relays 518 and 516 and magnet 519, thus allowing the record set up on registers 600, 601, etc. to be transferred over the set of conductors 561 to the corresponding marker.

It will be remembered that when the sender selector vertical magnet 309 operated, ground was connected by means of the cross-connecting block 370 to the winding of frame identifying relay 511. When, therefore, marker relays 410 and 411 operate as a result of the marker being seized, as described in the patent to S. B. Williams, above identified, ground is connected

through the left outer armature and contact of relay 410, conductor 451, contacts of sender connector 500, the right armature and front contact of relay 511, contacts of the sender connector 500, conductor 452, left inner armature and contact of relay 411, winding of starting relay 412, to battery at the armature of relay 421. Relay 412 operates in this circuit. If some other sender selector vertical magnet, as 338, whose armature is not cross-connected to the winding of relay 511 has been operated, relay 511 would be normal and the above traced ground would in this case be extended through the right armature and back contact of relay 511 to cause the operation of a different starting relay, as 413, associated with a second frame connector. It is evident, then, that by using a number of relays similar to frame identifying relay 511 the operation of certain sender selector vertical magnets will cause the operation of the corresponding frame connector starting relays similar to relays 412 and 413, thus causing the selected marker to be associated with the proper group of selector switches in which the selected trunk appears.

When relay 412 operates, a circuit is completed from battery through the lower winding of relay 414, upper armature and front contact of relay 412, right armature and back contact of relay 417, to ground at the armature and contact of relay 416. By means of the series circuit through the armature and contact of relay 412, no other relay similar to relay 414 can be energized, thus preventing simultaneous connections through the frame connector 400. A circuit is now completed through the slow release relay 416 from battery through its winding, left armature and back contact of relay 417, lower armature and contact of relay 414 to ground at the inner armature and contact of relay 410. Relay 416 attracts its armatures and completes an obvious locking circuit for relay 414 in series with the winding of relay 417. Relay 417 operates in this circuit and opens the energizing circuit for relay 416. When relay 416, which is slow-acting, has released, relay 418 operates from battery through its winding, uppermost armature and contact of relay 414, right armature and front contact of relay 417 to ground at the armature and contact of relay 416.

When marker relay 419 operates, as described in the above mentioned patent to S. B. Williams, ground is extended over conductor 450 through the contact of switch 300, conductor 158, armature and contact of relay 114, conductor 157 to battery through the winding of vertical magnet 210. Magnet 210 operates and connects ground through its lower armature and contact, conductor 240 to battery through the winding of frame connector relay 420. With relays

418 and 420 operated, the group of conductors 250 individual to switch 200 in which the selected trunk 120 has an appearance, are connected through contacts of 5 frame connector 400 to the marker testing mechanism 470 of the marker.

The switch 200 is now associated directly with the marker and tests are therein made in the manner described in the above-mentioned patent to S. B. Williams, resulting 10 in the operation of a trunk vertical magnet as 211, and a horizontal connecting magnet as 220.

The further extension of the calling line, 15 and the subsequent release of the connection are accomplished as described in the cited Williams patent.

What is claimed is:

1. In a telephone system, a number of 20 lines, a plurality of groups of selective switches, means for extending said lines to said switches, a controlling mechanism for said switches, an automatic switch for extending said lines toward said controlling 25 mechanism, a connector for each group of selective switches, each connector arranged for operation for connecting said mechanism to the switches of the corresponding group, means responsive to said automatic switch in its operation for selecting one of 30 said connectors to be operated, and means controlled by said mechanism for selectively operating the selective switch to which such mechanism is connected.
2. In a telephone system, telephone lines, 35 a number of selective switches, means for extending said lines to said switches, a controlling mechanism for said switches, an automatic switch having a plurality of operating members for causing the association of 40 said lines with said mechanism, connectors each relating to a different one of said selective switches arranged for operation to connect said mechanism to the corresponding 45 selective switch, discriminating means operable according to the operation of said
3. In a telephone system, telephone lines, selective switches, automatic means for extending connections over said lines to said switches, a controlling mechanism for said switches, an automatic switch having a plurality of rows of contacts, an operating member for each row, a plurality of said lines appearing in each row, means for operating 50 said members to cause said lines to be associated with said mechanism, connectors each related to a different one of said selective switches arranged to connect the controlling mechanism with such switch, means 55 variably operable in accordance with which one of said operating members is taken for use for selecting one of said connectors for operation, and means governed by the controlling mechanism for selectively operating the selective switch to which such mechanism is connected.
4. The combination with telephone lines of a number of selective switches, means for extending said lines to said switches, a register sender, a sender selector switch for extending said lines to said sender, a switch controlling marker, a connector for each selective switch, connectors each related to a different one of said selective switches arranged for operation for connecting said 75 marker to the corresponding selective switch, means for associating the sender with the marker, means responsive to the sender selector for determining which one of said connectors is to be operated, and means controlled by the marker through the connector for governing the operation of the selective switch with which said marker is associated.

In witness whereof, I hereunto subscribe 80 my name this 9 day of April A. D., 1924.

SAMUEL B. WILLIAMS.
